UNITED STATES PATENT OFFICE.

JOHN R. FERREN, OF BOYD, WEST VIRGINIA.

IRONING-TABLE.

1,255,399.

Specification of Letters Patent.

Patented Feb. 5, 1918.

Application filed August 17, 1916. Serial No. 115,484.

To all whom it may concern:

Be it known that I, JOHN R. FERREN, a citizen of the United States, residing at Boyd, in the county of Roane and State of West Virginia, have invented certain new and useful Improvements in Ironing-Tables, of which the following is a specification.

This invention relates to an improvement in ironing tables, and more particularly to devices of this nature in which a table, made in the form of a cabinet has an ironing board mounted in the upper part thereof to be swung down to form a part of the table top or to be swung to a raised position to be disposed in the proper relation for the proper use of the same.

An object of my invention is to provide an ironing board carrying and supporting structure which is so arranged that the board may be brought down to be flush with the remainder of the table top or may be moved to a raised position where it is disposed sufficiently above the top of the table that clothes may be readily placed thereon.

A further object lies in arranging means in conjunction with the supporting means for the board which will permit securement of the board to be held in rigid mounting in its raised position, and to provide means by which the board may be moved manually from one position to the other.

With the above and other objects in view, my invention consists in certain novel features of construction and combinations of parts which will be hereinafter set forth in connection with the drawings and then more particularly pointed out in the claims.

In the drawings:—

Figure 1 is a view in front elevation of a table constructed after the manner of my invention.

Fig. 2 is a top plan view of the structure disclosed in Fig. 1.

Fig. 3 is a longitudinal sectional view taken on the line 3—3 of Fig. 2.

Fig. 4 is a horizontal sectional view taken on the line 4—4 of Fig. 3.

The supporting structure as generally indicated at 1 is made of greater length and width than these dimensions of the ironing board figure, and this supporting structure

comprises the frame work 2 which may have drawer and cupboard compartments therein as indicated at 3 and 4. The exact construction and arrangement of the supporting structure is not an essential part of my invention, and hence I shall not here enter into a discussion of the detail arrangement of the portions below the supporting member 5 which is disposed somewhat down from the top edges of the rim portion 6 of the supporting table structure. A top 7 is disposed upon the upper edge of the rim portion 6 and is secured in place thereon in any observed manner, and in this way a compartment is formed between the supporting member 5 and the top member 7.

The top 7 is cut out in its central portion to have the opening thereof formed to the shape which it is desired that the ironing board take, this opening being indicated at 8.

An ironing board 9 is made of a configuration to fit within the opening 8 of the table top and to have a reasonably snug fit therewith, although it is desirable that the board have sufficient clearance with the opening that the covering as indicated at 10 can be stretched over the top thereof and brought down over the side edges to be secured beneath the board, and in some instances it may be found desirable to provide the table top 7 with a padded or other covering layer as indicated at 11, to give the same soft surface as is possessed by the ironing board proper.

Cross bars 12 and 13 are secured between the side rim members of the supporting structure in such relation that they rest upon the supporting member 5, and link like board supporting bearing members 14 and 15 are shaped to have portions thereof fitted in eye members 16 and 17 which are carried by the cross bars 12 and 13, the bearing or supporting members 14 and 15 being thus connected with the cross bars 12 and 13 in such relation that they may be swung down to rest against the supporting member 5 or may be raised to extend up beyond the top edge of the table rim and above the top surface of the table top by passing through the opening 8. The board 9 has batten strips 18 and 19 secured across the bottom side thereof.

and bearing eyes 20 are connected with these batten strips and have the supporting members 14 and 15 mounted therethrough in such relation that the board is connected with 5 these members and will be raised to a position of elevation above the top surface of the table-top 7 as the supporting members 14 and 15 may be elevated.

It is not a purpose of the supporting members 14 and 15 that they shall be raised to lift the board to the proper operative relation, but rather these supporting members are intended only to hold the board at the proper elevation, and to raise the board to 10 the position shown in the dotted lines in Fig. 3, I provide a shaft 21 which is journaled in suitable bearings mounted at the approximate longitudinal center of the supporting member 5 so that this shaft 21 is disposed transversely thereacross and between the side rim members. The shaft 21 has an offset portion as indicated at 22, and this offset portion is received through a suitable bearing provided at 23 on the lower 15 side of the board 9, the parts being thus so arranged that as the shaft 21 is turned the offset portion 22 will be swung to an upright position and consequently the board 9 will be carried therewith to raise the board 20 to a relation in which it is mounted on the supporting members 14 and 15.

A chain 24 or other suitable means is connected between the board 9 adjacent to the batten 19 and a screw eye 25 provided in the 25 supporting member 5, and thus the board is held against excessive swinging movement. However, it is preferable that this chain 24 or other means, be made of such a length that the supporting members 14 and 15 will 30 swing past a vertical center and thus the board will be held against return swinging movement to the position of fitting within the opening 8. It is also preferable that some means be provided to hold the board 35 in the raised position and against return movement as when the iron is being run over the board sufficient force may be exerted to cause the same to be displaced and moved to the lowered position, and to guard 40 against such a contingency, I provide the hook member 26 which is connected adjacent to the batten 18 and which is adapted to connect in a screw-eye 27 carried in the supporting member 5. A handle 28 is provided on the outer end of the shaft 21, this handle being extended to the forward side of the table rim, and thus the shaft 21 may 45 be manually turned to bring the board to the raised and lowered position, it of course 50 being understood that when the board has been lowered it will be held against raising movement by its own weight and will have the top surface thereof presented to form a smooth and continuous surface with the table-top. 55

From the foregoing it will be seen that I have provided a device which at once offers a desirable form of ironing board supporting table embodying in its construction a clothes press and that the structure as assembled in the disclosure made in the dotted lines of Fig. 3 will present the board in a position to be used for all ordinary ironing. The screw-eye 29 forms means to hold the hook 27 in a raised position when it is desired to lower the board and thus present the structure in such form that the raising and lowering of the board may be readily accomplished.

While I have herein shown and described only one specific form of the structure, it will be understood that a number of variations and changes might be resorted to in the form and arrangement of the several parts making up the structure without departing from the spirit and scope of my invention, and hence I do not wish to be limited to the exact disclosure but rather only to such points as may be set forth in the claims.

I claim:

1. An ironing table comprising a supporting structure having a top thereon, said top having a central opening shaped to have the form of a standard ironing board, an ironing board mounted in conjunction with the supporting structure to swing down within the opening thereof and form a continuation of the top and to be raised and elevated above the top for use, a shaft extending through the supporting structure and provided with an off-set portion hingedly connected with the ironing board, and a handle connected to said shaft and extended to be accessible exteriorly of the supporting structure through which manual turning of the shaft may be accomplished to thus obtain desired movement of the ironing board to the raised position.

2. An ironing table comprising a supporting structure having a top rim, a supporting member mounted across between the sides of the top rim below the upper edges thereof, a table top mounted upon the rim and provided with a central opening shaped to have the form of a standard ironing board, an ironing board shaped to be received within the opening of the table top to form a continuation of the surface thereof, connecting links arranged between said ironing board and the supporting member to mount the ironing board to be capable of movement to close within the opening and movement to rise and be supported above the top of the table, means to secure the ironing board against swinging movement to hold the same in the raised position, a shaft extended through the supporting structure to be held upon the supporting member and provided with an offset portion hingedly 130

B

connected with the ironing board, and a handle connected to said shaft and extended to be accessible exteriorly of the supporting structure to allow manual turning of the shaft and to thus accomplish the desired movement of the ironing board.

In testimony whereof I affix my signature in presence of two witnesses.

JOHN R. FERREN.
